Attorney

UNITED STATES PATENT OFFICE.

JAMES BROPSON, OF CLEVELAND, OHIO.

ROOF-FLASHING.

1,299,423.

Specification of Letters Patent.

Patented Apr. 8, 1919.

Application filed January 30, 1919. Serial No. 274,053.

To all whom it may concern:

Be it known that I, JAMES BROPSON, a citizen of the United States, residing at Cleveland, in the county of Cuyahoga and State of Ohio, have invented certain new and useful Improvements in Roof-Flashings, of which the following is a specification.

This invention relates to flashings for roofs, and is particularly adapted for use on flat roofs, to make a tight joint around a pipe or the like extending through the roof. A feature of the invention is the use of two rings between which the roofing, or a plate applied thereto, is clamped with a novel 15 form of packed joint, whereby leak is prevented not only between the flashing and the pipe, but also between the flashing and the adjacent part of the roof.

In the accompanying drawings, Figure 1 20 is a plan view of the flashing. Fig. 2 is a sectional view.

The flashing comprises an upper ring 6 and an under ring 7, and the pipe is indicated at 8. The ring 6 has an inner depending 25 part or flange 9 which projects within the opening 10 in the lower ring, a channel 11 being formed on the under side of the upper ring, into which channel a rib or lip 12 on the lower ring projects. Packing 13 of asbestos 30 or the like, is placed in the channel 11 where it is held by the rib 12 on the lower ring, the rings being secured together by bolts or rivets 14 which also extend through the roofing plate or material 15, or, instead of 35 the roofing material, a plate of lead or other material, which is extended into the roofing may be used, and securely clamped by the rivets to the rings.

The space between the pipe 8 and the ring 6 is filled with a packing 16 of lead or similar material, tamped into place, and the

ring has a groove 17 into which the packing is forced, and this groove assists in holding the packing in place.

By the means described, a tight joint is 45 made between the flashing and the roof as well as between the flashing and the pipe, and a flashing is produced which will be water-tight for an indefinite period under ordinary conditions. 50

I claim:

1. A flashing comprising upper and lower rings, the upper ring having a channel in its under side, and the lower ring having a rib fitting in said channel, packing between the 55 rib and the channel, and a roof plate having an opening receiving said rings, the edge of the plate around said opening being clamped between said rings.

2. The combination with a roof plate or 60 layer having an opening, of upper and lower rings between the outer edges of which the roof plate is clamped around said opening, one ring having a channel near its inner edge and the other ring having a rib near 65 its inner edge fitting in said channel, and packing in the channel.

3. A flashing comprising the upper ring 6 having a depending flange 9 at its inner edge, and a channel 11 in its inner side, the 70 lower ring 7 having an opening into which said flange projects and also having a rib 12 fitting in said channel, packing in the channel and fastening devices between the 75 rings, adapted to clamp a roof plate between said rings.

In testimony whereof, I do affix my signature in presence of two witnesses.

JAMES BROPSON.

Witnesses:

JOHN A. BOMMHARDT,
ROBERT L. BRUCK.
